F i g. 4

This application is a continuation-in-part of my earlier filed application Serial No. D. 57,678, filed September 25, 1959, which is now abandoned.

I claim:

The ornamental design for a chair, as shown and described.
